UNITED STATES PATENT OFFICE.

JOHN ELLWOOD LEE, OF CONSHOHOCKEN, PENNSYLVANIA, ASSIGNOR
TO JOHNSON AND JOHNSON, OF NEW BRUNSWICK, NEW JERSEY, A
CORPORATION OF NEW JERSEY.

DESIGN FOR A JAR.

No. 37,829.

Specification for Design.

Patented Feb. 20, 1906.

Application filed December 11, 1905. Serial No. 291,351. Term of patent 14 years.

To all whom it may concern:

Be it known that I, JOHN ELLWOOD LEE, a citizen of the United States of America, residing in Conshohocken, in the county of Montgomery, in the State of Pennsylvania, have invented a certain new, original, and ornamental Design for a Jar, of which the following is a specification, reference being had to the accompanying drawings, forming a part thereof, in which—

Figure 1 is a side elevation, and Fig. 2 is a plan view.

The views of the jar, showing my new design, appear in the above drawings.

I claim—

The ornamental design for a jar, as shown.
JOHN ELLWOOD LEE.
